SLEEPER COACH ARRANGEMENT

Henry G. McCarroll, Detroit, Mich., assignor to
The Dow Chemical Company, Midland, Mich., a
corporation of Michigan

Application February 8, 1938, Serial No. 189,390

12 Claims. (Cl. 105—315)

This invention relates to a sleeper coach design and has particularly to do with buses, trains, or other vehicles which are adapted to be used both as day coaches and sleeping coaches.

In the conventional type of Pullman or sleeping car having upper and lower berths there are many disadvantages and discomforts which must be endured by the passengers. These cars must be made over from a day coach to sleeping car by the porter all at one time, and as a rule, the upper berths are very undesirable since they can be reached only by the use of a ladder. In addition, the dressing facilities are inconvenient and there is no convenient storage space for garments during the night or for bags during the day.

Some attempts have been made to correct these faults but these attempts, though they have sometimes resulted in more convenience to the passenger, have been unsuccessful since they have resulted in less passenger space in the car as a whole, and in greater construction costs thereby keeping the more convenient facilities out of reach of the normal passenger's ability to pay.

It is, therefore, an object of the present invention to provide a sleeper coach which will hold a maximum number of passengers and yet which does away with the inconveniences normally experienced by passengers in a sleeper coach.

The present invention contemplates a center-aisled car provided with compartments on each side thereof which, though they form upper and lower compartments, are equally accessible from the aisle. A further object of the invention is to provide compartments so arranged that standing space is provided therein whether the compartments are arranged for day use or sleeping use.

An additional feature of the invention consists in the bed arrangement whereby ample storage space is provided for luggage where it will be out of sight and yet conveniently accessible either day or night. Furthermore, the occupant of any one berth may retire at will by simply opening his bed without the aid of a porter and without disturbing other passengers in the coach.

Other objects and features of the invention have to do with this sleeper arrangement for buses, train or transport aircraft and with details of construction and fabrication as will be clearly brought out in the following specification and claims.

Certain constructions in accordance with the invention are illustrated by way of example, in the accompanying drawings in which:

Fig. 1 is a perspective view of one side of the sleeper coach showing the upper and lower compartments arranged for day use and sleeping purposes.

Fig. 2 is a longitudinal section of a sleeper coach showing the arrangement of the berths.

Fig. 3 is a partial sectional plan view of one side of the coach taken on lines 3—3 of Fig. 2.

Fig. 4 is a partial section taken on the lines 4—4 of Fig. 2.

Fig. 5 is a foreshortened sectional view taken on the lines 5—5 of Fig. 2.

Referring to Figs. 1 and 2 where one side of the interior of the sleeper coach is illustrated, vertical L-shaped upper and lower compartments are arranged longitudinally of the corridor or central aisle. In the particular modification illustrated, the lower compartments are in an upright L-position. The upper compartments are in inverted and reversed L-position. In either of these compartments the vertical portions are of sufficient height to provide standing room. Also the length of the horizontal portions together with the width of the vertical portion forms a space exactly long enough for a bed in sleeping position. It will be noted that the compartments are arranged so that the horizontal portion in each case is vertically adjacent the vertical portion of an adjacent compartment.

Each compartment is provided with a berth which, in the preferred arrangement, is divided in two sections. One section is permanently located in the horizontal portion of the compartment. The other section is hinged to the permanent section of the berth and may be swung in a horizontal or vertical position. When in horizontal position the combined portions form a bed of normal length.

More specifically with reference to Fig. 1, a longitudinal supporting beam 6 supports a floor 7 for a central corridor. A side panel 8 joins a roof panel 9 and a floor panel 10, the latter being located below the corridor level and between the beam 6 and the side panel. A horizontal panel 11 positioned above the corridor floor level, provides a floor for the upper compartments and also serves as the top of the horizontal portion of the lower compartment, while a panel 12 joins with panel 11 and closes the horizontal portion of the lower compartments from the corridor. The top of the lower compartment is enclosed by a panel 13 which also

serves as the lower panel of the horizontal portion of the upper compartment. Between the panels 13 and the roof panel 9 is a closing panel 14 which encloses the horizontal portions of the 5 upper compartment from the corridor. It will be noted that the vertical portions of each of the compartments are open to the corridor. Sliding curtains 15 are provided for these doorways or 10 corridor openings and these curtains are arranged to be securely fastened across the openings to serve somewhat as a safety member. Each of the compartments is furnished with a window 16 in the side panel 8.

The back of the lower compartment is formed 15 by a vertical panel 17 which also forms the front of the horizontal leg of the lower compartment. The front part of the vertical leg of the lower compartment is formed by a panel 18 which will be later referred to in greater detail. This panel 18 also provides a back for the lower vertical portion of the upper compartment.

Each compartment is provided with a standard passenger seat. These seats may be double or single, but in the present exemplification are 25 shown as single seats. In the lower compartment a seat 20 is shown positioned against the back panel 17 and a seat back 21 is pivotally mounted at 21a at the back of the seat 20 so that it may be folded down upon the seat 20.

30 In the upper compartment, a seat 22 is positioned at the back of the compartment against the panel 18 and each seat has a back 23. It will be seen from Fig. 1 that the width of this seat is about half that of the compartment so 35 that considerable standing room is afforded in each compartment. Beside the seat in the upper compartment is a step 24 which serves two purposes. It may be used to aid a passenger in entering the upper berth, as will be later described. 40 In addition, it provides, along with the seat 22, a recess in the lower portion of the back of the panel which is utilized in connection with the storage of the lower berths.

Each of the compartments is provided with 45 berths. These berths are preferably arranged as hereinafter described though any arrangement which fulfills the purpose will be in accordance with the invention. Referring, first, to the berths in the lower compartments, a berth section or 50 panel 25 having a width which is substantially less than the width of the compartment, is horizontally and permanently disposed in the horizontal leg of the compartment. This panel 25 abuts and is supported at the outside edge by the 55 side panel 8. At the front edge it abuts the panel 17 and at its free corner it is supported by a single leg 26a (Figs. 2 and 3). Another berth panel 26 is hinged at 27 to the rear edge of the panel 25 so that it may be vertically or 60 horizontally disposed. On these panels 25 and 26 is a bed 28 which folds in the middle when the panel 26 is in vertical position. A latch 29 is provided to hold the panel 26 upright. As previously mentioned, the back of the panel 18 65 is formed with a recess which will receive the top portion of the bed 28 and panel 26 when in vertical position so that the panel 26 will be flush with the panel 18 (see Fig. 2). When in this vertical position the panel 26 will form a forward 70 wall of the vertical section of the lower compartment and will hide from view the bedding attached to berth sections 25 and 26.

In the upper compartments the berths are formed also of a movable and a permanent section. The permanent section consists of the 75

panel 13 which is the dividing panel between horizontal portion of the upper compartment. The berth portion of this panel is of substantially less width than the compartment. At the forward edge of the upper permanent berth panel 5 13 a movable section 30 is hinged as at 31. A latch 32 is provided to hold the berth section 30 in vertical closed position. Suitable means are provided on the rear face of the dividing panel 11 to furnish support for the free edge of the 10 berth section 30 when it is in horizontal position. A bed 33 is arranged on the berth sections 13 and 30 so that it will fold with the movable section 30.

It will thus be seen that I have arranged upper and lower compartments in which standing room 15 is always available regardless of whether or not the berths are in sleeping position. This has been accomplished with a compartment which is no longer than the usual length of a berth. In addition the latches 29 and 32 are so arranged 20 that they may be easily manipulated by the passenger so that he may convert the compartment into a sleeping compartment simply by lowering the berth sections 26 or 30 into horizontal position. In the lower compartments the seat back 25 21 is to be folded down (Fig. 2) before the section 26 is lowered. In the upper compartments the step 24 may be used to help the passenger into the berth though, since the berths are only waist-high, no difficulty will be experienced in 30 gaining access thereto. It will be noticed that the conversion of the compartments may be accomplished without inconveniencing or disturbing the occupants of the other compartments. The beds will be made up by the porter in the 35 morning so that they will be ready for occupancy whenever the passenger desires.

Each compartment is arranged so that baggage may be stored in the horizontal leg of the L. In the upper compartment the baggage may be 40 stored along side the berth on the panel 13. Here it is available day or night and need not be moved when the compartment is converted. Similarly, in the lower compartment baggage may be stored on the floor 10 along side and/or 45 under the berth section 26. With these facilities the seating compartments are free of encumbrances. Each compartment may be furnished with standard equipment in the way of lavatories, mirrors and toilets.

The nesting arrangement of the compartments in the embodiment shown in Figs. 1 and 2 consists in having the lower compartment in an upright L position and the upper compartment in an inverted L position and nestled with the 55 lower compartment. Other arrangements of these compartments may be had without departing from the applicant's invention. In other words, the upper compartments may be inverted L's with the horizontal leg pointing to the front 60 of the vehicle while the lower compartments are upright L's having the vertical portion in each case vertically adjacent the horizontal portion of the upper compartments.

What I claim is:

1. In a sleeper coach having a central corridor, a floor for said corridor, L-shaped upper and lower compartments in said coach arranged longitudinally on each side of said corridor and in nestled relationship, each of said compartments having a vertical portion and a horizontal portion and vertical doorways between the vertical portions and the corridor, floors in said lower compartments disposed at a level lower than the corridor floor, floors in said upper compart- 75

ments disposed at a higher level than the corridor floor, seats on the floors of said compartments, and a bed longitudinally arranged in each of said compartments comprising a permanently positioned portion disposed in the horizontal portion of each compartment, and a movable portion disposed for day use at right angles to said first portion to form a closing wall for said horizontal space and disposed, when converted for night use, in horizontal alignment with said first portion and extending across said vertical portion of the compartment.

2. In a convertible sleeping vehicle, L-shaped upper and lower compartments arranged longitudinally of a corridor and in nested relationship, each of said compartments having a vertical portion and a horizontal portion, floors in said lower compartments disposed at a level lower than the corridor floor, floors in said upper compartments disposed at a higher level than the corridor floor, seats on the floors of said compartments and a bed in each of said compartments adapted to be stored in the horizontal portions of said compartments, and adapted to be disposed longitudinally for night use with a section in the horizontal and vertical portions of said compartments, said bed having a width less than that of the compartment whereby to provide standing room.

3. In a sleeper coach having a longitudinal corridor, a series of longitudinally spaced compartments arranged along said corridor, said compartments comprising lower L-shaped compartments and upper inverted L-shaped compartments nested within each other whereby the horizontal portion of each of a plurality of compartments is adapted to lie vertically adjacent the vertical portion of an adjacent compartment, floors in said compartments, a raised floor in said corridor disposed at a level between the floor levels of said compartments, seats in said compartments, and a split bed in each of said compartments comprising a permanently positioned portion disposed in the horizontal portion of each compartment, and a movable portion disposed for day use substantially at right angles to said first portion, and disposed, when converted for night use, in horizontal alignment with said first portion across the vertical portion of said compartments.

4. In a sleeper coach having a longitudinal corridor, a series of longitudinally spaced compartments arranged along said corridor, said compartments comprising lower L-shaped compartments and upper inverted L-shaped compartments nested within each other whereby the horizontal portion of each of a plurality of compartments is adapted to lie vertically adjacent the vertical portion of an adjacent compartment, floors in said compartments, a raised floor in said corridor disposed at a level between the floor levels of said compartments, seats in said compartments, and a bed in each of said compartments adapted to be disposed longitudinally for night use across the entire horizontal length of said compartments.

5. A car provided with a corridor, and having upper and lower compartments arranged longitudinally of, and communicating with, said corridor, each of said compartments being L-shaped, the horizontal leg of each L-shaped compartment being adapted to lie vertically adjacent the vertical leg of an adjacent compartment, seats in said compartments, and movable beds independent of said seats and adapted to lie par-

tially in said horizontal legs and partially in the vertical portions of said compartments, the beds being arranged to extend substantially the full length of the compartments when in sleeping position.

6. In a coach, permanent upper and lower L-shaped, individual compartments arranged longitudinally on each side of a central corridor, each of said compartments having vertical doorways communicating with said corridor, the horizontal space of each of said compartments being arranged vertically adjacent the vertical space of an adjacent compartment, seats in the vertical portion of the compartments, and a bed in each of said compartments having a portion disposed in said horizontal space and having a portion adapted to lie in horizontal position to form a completed bed, said beds having a length equal to that of the compartments and a width substantially less than that of the compartments, whereby to provide standing room at all times in the vertical portion of said compartments.

7. In a convertible sleeping vehicle, L-shaped upper and lower compartments arranged longitudinally of a corridor and having a horizontal length equal to that of a normal berth, each of said compartments having a horizontal and vertical portion, and being dimensioned to permit a nesting arrangement of adjacent compartments, a seat in each of said compartments, and a bed in each of said compartments independent of said seats and adapted to be disposed longitudinally for night use with a section in the horizontal and vertical portions of said compartments.

8. In a sleeping vehicle provided with a central corridor, a plurality of permanent individual upper and lower compartments arranged longitudinally of and communicating with said corridor, each of said compartments being L-shaped and having a horizontal length equal to that of a normal berth, and a vertical length to provide standing room for a normal person, a seat in each of said compartments, and a bed in each compartment to be formed independently of said seats, a portion of said bed being mobile to make available the vertical portions of said compartments, other than the space occupied by the seats, for standing room during day use.

9. In a sleeper coach having a corridor, a floor for said corridor, L-shaped upper and lower compartments in said coach arranged longitudinally of said corridor and in nested relationship, each of said compartments having a vertical portion and a horizontal portion, floors in said lower compartments disposed at a level lower than the corridor floor, floors in said upper compartments disposed at a higher level than the corridor floor, seats on the floors of said compartments, and a bed longitudinally arranged in each of said compartments comprising a permanently positioned portion disposed in the horizontal portion of each compartment, and a movable portion disposed for day use at right angles to said first portion and disposed, when converted for night use, in horizontal alignment with said first portion thereby extending across said vertical portion of the compartment.

10. In a convertible sleeping vehicle, L-shaped upper and lower compartments arranged longitudinally of a corridor and having a horizontal length equal to that of a normal berth, each of said compartments having a horizontal and vertical portion, and adapted to be nested, said lower compartments being upright L's and said

- upper compartments being inverted L's, a seat in each of said compartments, a bed in each of said upper compartments comprising a permanent section disposed horizontally at all times 5 along the bottom of the horizontal portion of said compartments and a movable section adapted to extend across the vertical portion of said compartment, and a bed in each of said lower compartments comprising a permanent section 10 disposed horizontally and substantially midway between the bottom and the top of the horizontal portion of said lower compartments and a movable section adapted to extend across the vertical portion of said lower compartment, said beds in each of said compartments being of substantially 15 less width than that of said compartments and lying adjacent the side thereof whereby to form an easily accessible baggage space in said horizontal portions for day use and standing room 20 in said vertical portions for day or night use.
11. In a convertible sleeping vehicle, L-shaped upper and lower compartments arranged longitudinally of a corridor and having a horizontal length equal to that of a normal berth, each of 25 said compartments having a horizontal and vertical portion, the horizontal portion of each compartment being disposed vertically adjacent the vertical portion of an adjacent compartment, said lower compartments being upright L's and said 30 upper compartments being inverted L's, a seat in each of said upper compartments, a bed in each of said upper compartments comprising a permanent section disposed along the bottom of the horizontal portion of said compartments and
- a movable section adapted to extend in alignment with said permanent section and across the vertical portion of said compartment over said seat, a seat in each of said lower compartments, a folding back on said seat, and a bed in each of 5 said lower compartments comprising a permanent section disposed substantially midway between the bottom and the top of the horizontal portion of said lower compartments and a movable section adapted to extend across the vertical portion of said lower compartments over 10 said last named seat with the back in folded position, said bed in each of said compartments having a width less than that of said compartments and lying adjacent a side of said compartment whereby to form baggage space between said beds and the other side of said compartments. 15
12. In a sleeper coach having a longitudinal corridor, a series of longitudinally spaced compartments arranged along said corridor, said compartments comprising upper and lower L-shaped compartments positioned adjacently in nested relation, and beds in each of said compartments adapted to lie substantially the full 20 length of the compartment when in sleeping position and comprising a portion permanently positioned in the horizontal portions of said compartments and a pivoted portion adapted to be moved from a substantially vertical storage position to a horizontal sleeping position in alignment with said permanently positioned portion. 25

HENRY G. McCARROLL.
